2 SHEETS—SHEET 2.

UNITED STATES PATENT OFFICE.

JOHN C. TALIAFERRO, OF BALTIMORE, MARYLAND, ASSIGNOR TO CONTINENTAL CAN COMPANY, INCORPORATED, OF SYRACUSE, NEW YORK, A CORPORATION OF NEW YORK.

EXHAUST-BOX FOR CANNING MACHINERY.

1,274,956.

Specification of Letters Patent.

Patented Aug. 6, 1918.

Application filed October 18, 1917. Serial No. 197,414.

To all whom it may concern:

Be it known that I, JOHN C. TALIAFERRO, a citizen of the United States, residing at Baltimore city, State of Maryland, have invented certain new and useful Improvements in Exhaust-Boxes for Canning Machinery, of which the following is a description, reference being had to the accompanying drawing and to the figures of reference marked 10 thereon.

The invention relates to new and useful improvements in exhaust boxes for canning machinery, and more particularly to an exhaust box wherein the cans are caused to 15 travel continuously through the box.

An object of the invention is to provide an exhaust box having a casing through which the filled cans to be treated pass, and wherein the cans are moved through the casing by a rotating drum, which drum also serves as a medium for supplying steam to the exhaust box.

A further object of the invention is to provide an exhaust box of the above character with means whereby two rows of cans may be simultaneously fed through the casing by the same rotating drum, thus greatly reducing the speed of the cans without reducing the number of cans treated in a given 30 period of time.

These and other objects will in part be obvious and will in part be hereinafter more fully disclosed.

In the drawings, which show by way of 35 illustration one embodiment of the invention:—

Figure 1 is a view in longitudinal section through an exhaust box having my improvements applied thereto;

Fig. 2 is an enlarged sectional view of a 40 portion of the rotating drum;

Fig. 3 is a view, partly in plan and partly in section, of the same;

Fig. 4 is a vertical sectional view through 45 the machine.

In carrying out the invention, I have provided an exhaust box which consists of a supporting frame on which is mounted an elongated casing, open in part at each end 50 so as to permit the cans to pass in at one end of the casing, then through the casing, and out at the other end thereof. Extending longitudinally in the casing is a rotating drum having a projecting thread spi-

rally wound thereon, which thread engages the cans and gradually forces the same through the exhaust box. This drum is perforated and is supplied with steam, preferably through a central pipe which extends from end to end of the drum. The casing forming the exhaust box is divided centrally above the drum so that two rows of cans may be simultaneously fed through the exhaust box and by the same rotating drum. The inner walls of the exhaust box are formed with supporting ledges which assist the drum in supporting the cans as they are fed through the exhaust box.

Referring more in detail to the drawings, my improved exhaust box consists of a supporting frame 1, on which is mounted a casing 2. This casing 2, as clearly shown in Fig. 4, is formed with side walls 3—3 and top and bottom walls 4—4. The casing is preferably rectangular in cross section and is elongated so that the cans may be fed through the casing, entering at one end and leaving at the other, and while passing through the casing they may be subjected to steam. The casing is partly open at each end.

Extending longitudinally of the casing is a rotating drum 5. This rotating drum is hollow and is closed at its ends by heads 6—6 which are formed with projecting sleeves, and these sleeves are mounted in suitable bearings in the frame 1. The drum is preferably rotated by a sprocket wheel 7.

Extending longitudinally through the drum is a pipe 8. This pipe may also act as a tie-rod for the journals of the rotating drum. Said pipe is plugged at 9 to close one end thereof, while the other end of the pipe is connected to a steam supply 10. This pipe 8 is formed with a series of perforations 11.

The drum 5 is also provided with a series of perforations 12, and is further provided with a projecting thread 13 which extends spirally about the drum from end to end thereof. The casing 2 is formed with supporting brackets 14 and 15, and with a central guiding rail 16. This guiding rail is mounted on hangers 17 attached to the upper wall of the exhaust box. There is also a side guide rail 16' which is attached to the side wall 3 of the casing 2. As clearly shown in Fig. 4, the brackets 14 and 15 ex-

tend only a short distance toward the center of the casing and the thread on the drum projects through the space between these brackets.

- 6 The cans are delivered to the exhaust box on a rotating disk 18 which may be driven by a suitable spiral gear 19 on the extended sleeve of the rotating drum. The spiral gear wheel 19 meshes with a coöperating gear on the hub of the disk 18. The cans are delivered onto the disk 18 in any suitable way, and as the disk rotates the cans are brought against the guide 20.
- 15 At the entrance of the casing 2 there is a pivoted dividing trigger 21. This pivoted dividing trigger is supported by the casing above the disk 18 and is formed with an enlarged rear end. This trigger operates automatically to direct first a can on the left 20 of the central guide 16 in the exhaust box, and then on the right of said central guide. As a can engages the rear end of the trigger, it will shift the same so that the next can will pass on the other side of the guide as above noted. In other words, the cans through the operation of this trigger are automatically and equally distributed on opposite sides of the central guide rail 16.
- 25 The cans rest in part on the bracket and 30 in part on the drum and as the drum rotates the spiral thread thereon will force the cans along the exhaust box and finally deliver the same from the opposite end thereof. The drum, as viewed from the receiving end of the exhaust box, rotates in a counterclockwise direction, as indicated by the arrow in Fig. 4. This rotation of the drum tends to hold the cans against the respective guide rails 16 and 16.
- 40 As above noted, there is a steam pipe passing centrally through the drum and, therefore, the drum will be supplied with steam, and inasmuch as the drum is perforated jets of steam will issue from the 45 drum in and about the cans being conveyed through the exhaust box. These perforations in the drum may be formed of such size and distributed so as to meet the required conditions. If desired, the perforations at the receiving end of the exhaust 50 box may be greater in number so that a greater amount of steam is supplied at the receiving end of the box or, if desired, the number of perforations may be greater at 55 the other end of the exhaust box.

60 After the cans are passed through the exhaust box they are delivered onto receiving disks which, as herein shown, are two in number. The disk 22 is a rotating disk 65 and coöperates with a closing machine so that the cans will be delivered directly to the closing machine from this disk. A suitable guide 23 may be provided for directing the cans into the closing machine. The disk 24 is also rotated and delivers the cans onto

a disk 25 from which they are delivered to a closing machine. Guide rails 26 and 27 are provided for directing the movement of the cans

The receiving disk 18 is preferably located so as to receive the filled cans from a filling machine, and from this disk the cans are passed in a double line through the exhaust box. By directing the cans in a double line through the exhaust box they 70 may be carried through the same at a slower speed without reducing the number of cans treated in the exhaust box in a given time. This slower speed not only gives the cans a greater period of time in the exhaust box, 75 but also greatly facilitates the handling of the cans without spilling the contents thereof.

It will be understood that I do not limit myself in this application to the particular 80 use of the exhaust box shown, as the invention consists broadly in the construction of the exhaust box and the disposition of the rotating drum therein whereby the cans may be conveyed through the exhaust box 85 by the rotating drum and steam supplied to the exhaust box through said drum. It is also obvious that minor changes in the details of construction and the arrangement of parts may be made without departing from 90 the spirit of the invention as set forth in the appended claims.

Having thus described the invention, what is claimed as new is:—

1. An exhaust box for canning machinery 100 including a casing, a rotating drum extending longitudinally of the casing, said drum having a spiral thread wound thereon, brackets coöperating with the drum for supporting the cans, and means whereby said 105 drum may simultaneously operate upon two rows of cans for feeding the same through the exhaust box.

2. An exhaust box for canning machinery 110 including a casing, a rotating drum extending longitudinally of the casing, said drum having a spiral thread wound thereon, brackets coöperating with the drum for supporting the cans, and means whereby said 115 drum may simultaneously operate upon two rows of cans for feeding the same through the exhaust box, said drum being hollow and having perforations therein, and means for supplying the drum with steam.

3. An exhaust box for canning machinery 120 including a casing, a drum extending from end to end of the casing and having a spiral thread for moving the cans through the casing, supporting brackets coöperating with the drum, and a guiding rail extending 125 lengthwise of the casing and centrally over said drum whereby two rows of cans may be simultaneously fed through the exhaust box by said drum.

4. An exhaust box for canning machinery 130

including a casing, a drum extending from end to end of the casing and having a spiral thread for moving the cans through the casing, supporting brackets coöperating with the drum, a guiding rail extending lengthwise of the casing and centrally over said drum whereby two rows of cans may be simultaneously fed through the exhaust box by said drum, a rotating disk for delivering the filled cans to the exhaust box, and a dividing trigger operated by the cans for directing the cans alternately to the opposite sides of the said central guide rail.

5. An exhaust box for canning machinery including a casing, a drum extending from end to end of the casing and having a spiral thread for moving the cans through the casing, supporting brackets coöperating with the drum, a guiding rail extending lengthwise of the casing and centrally over said drum whereby two rows of cans may be simultaneously fed through the exhaust box by said drum, a rotating disk for delivering the filled cans to the exhaust box, a dividing trigger operated by the cans for directing the cans alternately to the opposite sides of the said central guide rail, said drum being hollow and perforated, a perforated pipe extending from end to end of said drum centrally thereof, and means for supplying steam to said pipe.

10. The exhaust box of claim 5, further including a central guide rail extending lengthwise of the casing and centrally over said drum whereby two rows of cans may be simultaneously fed through the exhaust box by said drum, a rotating disk for delivering the filled cans to the exhaust box, a dividing trigger operated by the cans for directing the cans alternately to the opposite sides of the said central guide rail, said drum being hollow and perforated, a perforated pipe extending from end to end of said drum centrally thereof, and means for supplying steam to said pipe.

15. The exhaust box of claim 5, further including a central guide rail extending lengthwise of the casing and centrally over said drum whereby two rows of cans may be simultaneously fed through the exhaust box by said drum, a rotating disk for delivering the filled cans to the exhaust box, a dividing trigger operated by the cans for directing the cans alternately to the opposite sides of the said central guide rail, said drum being hollow and perforated, a perforated pipe extending from end to end of said drum centrally thereof, and means for supplying steam to said pipe.

20. The exhaust box of claim 5, further including a central guide rail extending lengthwise of the casing and centrally over said drum whereby two rows of cans may be simultaneously fed through the exhaust box by said drum, a rotating disk for delivering the filled cans to the exhaust box, a dividing trigger operated by the cans for directing the cans alternately to the opposite sides of the said central guide rail, said drum being hollow and perforated, a perforated pipe extending from end to end of said drum centrally thereof, and means for supplying steam to said pipe.

25. The exhaust box of claim 5, further including a central guide rail extending lengthwise of the casing and centrally over said drum whereby two rows of cans may be simultaneously fed through the exhaust box by said drum, a rotating disk for delivering the filled cans to the exhaust box, a dividing trigger operated by the cans for directing the cans alternately to the opposite sides of the said central guide rail, said drum being hollow and perforated, a perforated pipe extending from end to end of said drum centrally thereof, and means for supplying steam to said pipe.

forated, and means for supplying steam to the drum.

6. An exhaust box for canning machinery including a casing, a drum extending from end to end of the casing and having a spiral thread for moving the cans through the casing, supporting brackets coöperating with the drum, a guiding rail extending lengthwise of the casing and centrally over said drum whereby two rows of cans may be simultaneously fed through the exhaust box by said drum, a rotating disk for delivering the filled cans to the exhaust box, a dividing trigger operated by the cans for directing the cans alternately to the opposite sides of the said central guide rail, said drum being hollow and perforated, a perforated pipe extending from end to end of said drum centrally thereof, and means for supplying steam to said pipe.

In testimony whereof, I affix my signature, in the presence of two witnesses.

JOHN C. TALIAFERRO.
